UNITED STATES PATENT OFFICE.

WILLIAM HARRY JOSLIN, OF SOUTH SCITUATE, RHODE ISLAND.

DESIGN FOR A BOX.

52,767.

Specification for Design.

Patented Dec. 17, 1918.

Application filed June 5, 1918. Serial No. 238,397. Term of patent 14 years.

To all whom it may concern:

Be it known that I, WILLIAM HARRY JOSLIN, a citizen of the United States, residing at South Scituate, county of Providence, State of Rhode Island, have invented a new, original, and ornamental Design for a Box, of which the following is a specification, reference being had to the accompanying drawing, forming part thereof.

Figure 1 is a perspective view of a box, illustrating my new design.

Copies of this patent may be obtained for five cents each, by addressing the "Commissioner of Patents, Washington, D. C."

Fig. 2 is a side elevation showing the box in open position and the relative position of the eagle mounted on the open cover.

I claim:

The ornamental design for a box, as shown.

WILLIAM HARRY JOSLIN.
